UNITED STATES PATENT OFFICE

EDWARD C. HOFFMANN, OF BEAVER DAM, WISCONSIN

COOKING STOVE

Application filed May 18, 1928. Serial No. 278,663.

This invention relates to improvements in cooking stoves and consists in the novel construction hereinafter disclosed.

An object of the invention is to provide a stove having disappearing doors so that the stove, when not in use, may be converted into a cabinet form to conceal the stove structure proper and to furnish in the converted form a structure that may be used

10 as a kitchen cabinet.

The advantages of the structure will be apparent from the following detailed description thereof taken in connection with the accompanying drawings in which

15 Fig. 1 is a vertical transverse section through one end of the stove to illustrate particularly the foldable disappearing table top and its mounting.

Fig. 2 is a front elevation partially in section of one end section of the table top and its mounting.

Fig. 3 is a detail view of the retaining groove and guide rod for one of the table top sections.

25 Fig. 4 is a detail view of the hinge construction.

Fig. 5 is a front elevation of the upper portion of the stove of the invention.

Fig. 6 is a detail view taken in transverse 30 cross section of the mounting for the splash panel of the stove.

Fig. 7 is a further detail view of the mounting of the splash panel.

Fig. 8 is a horizontal section of the lower 35 part of the stove body showing the mounting and construction of the lower doors of the stove.

Fig. 9 is a front elevation of the lower door mounting.

40 Fig. 10 is a vertical section of the sliding hinge support for the lower door mounting.

In the embodiment of the invention illustrated in the drawings the stove is shown as including a stove body 1, a stove top 2, 45 a superstructure or hood 3 on the top of which is supported a warming oven 4. It is understood that the stove may be either of the coal, electric, fuel gas, gasoline or kerosene type and that the stove body may be provided with the usual openings for the

oven, fire pot and ash compartment when used with solid fuel, or that one or a plurality of ovens may be provided in the lower stove body where electric heating or gas fuel is used, each of these compartments being 55 closed in the usual way by suitable doors.

There are two sets of covering doors constructed in the stove, one of which is adapted to be concealed in the side walls of the superstructure or hood and to be moved forward 60 from a vertical position to a horizontal position across the forward part of the cooking top, and a lower set of doors concealed in the side walls of the stove body proper, said doors being adapted to fold across the front 65 of the stove body to conceal the front face of the stove body.

The stove is also provided with an adjustable splash panel that is arranged to move forward when the stove is in closed adjustment over a part of the cooking top, so that when the stove is converted into a cabinet all of the usual faces of the stove used as a cooking appliance are concealed.

The side walls of the superstructure or 70 hood of the stove are formed by spaced plates 5 and 6, which walls are transversely connected by a back plate 7. The spaces between the walls 5 and 6 form compartments in which the pivoted table members are concealed when the stove is in open adjustment.

The table members comprise plates 8 preferably having inturned flanges along the front and lower edges thereof. In the corners formed by the intersection of these 85 flanges are secured brackets 9 from each of which there extends beyond the rear edge of the member 8 a rod 10, said rod operating through an opening in a bracket 11 supported by the inner face of the inner wall 6 adjacent to the bottom thereof. The rod 10 has on its rearward extremity a notched disc 12 which cooperates with a detent or abutment 13 on the rearward face of the bracket 11. As the table member 8 is pulled out over the forward part of the stove top the rod 10 is extended through the bracket 11 until the disc 12 comes in contact with the bracket 11 thus 95 limiting its outward movement.

Near the top of the member 8 when it is in 100

vertical adjustment, and extending inwardly from the inner face thereof, is a rail 14 having a rounded extremity that seats in a groove in a guide strip 15 attached to the inner face of the wall 6. As soon as the member 8 is moved to vertical adjustment and starts to move into the concealing compartment the rail 14 enters the guideway 15 and serves to hold the member 8 in such adjustment that it may be readily moved backwardly or forwardly in the compartment.

It should be noted also that there is an angular bracket 16 supported by the inner face of the wall 6, so that the horizontal leg of the bracket 16 serves to support the outer edge of the member 8 when the member is inserted in and withdrawn from the concealing compartment.

When the member 8 is extended it covers the forward part of the stove top, it, of course, being understood that each of the members 8 on the opposite sides of the stove are oppositely hinged and fold towards each other forming a continuous horizontal support when in closed adjustment. This is the adjustment when the stove is not in use as a stove and the members 8 therefore in this adjustment form a table support or top. When it is desired to open the stove for use the members 8 are rotated upwardly to a vertical position in which condition the teeth in the discs 12 contact with the detents 13 respectively thus limiting the rotative movement and the inner edges of the members 8 are in vertical alinement with the openings at the front of the compartments formed by the walls 5 and 6. By pressure on the members 8 they are then moved rearwardly into the compartments, the rails 14 entering the guideways and serving to avoid friction in the movement. The forward openings of the compartments between the walls 5 and 6 into which the members 8 are inserted are provided with closures 17 having hinges 18 connecting them with the outer walls 5. The closures 17 may be spring-actuated to closed position so that when the members 8 are fully inserted in or withdrawn from the compartments said closures will spring to closed positions across the opening and give a finished appearance to the forward face of the hood walls.

The splash panel or wall member 20 is made adjustable so that it may be moved from a position parallel with and adjacent to the back plate 7 when the stove is in open adjustment, and when in closed adjustment forwardly against the back edge of the members 8. In order to provide for this adjustment of the splash panel there are mounted near the top of the outer faces of the walls 6 alined racks 19, said racks being formed with depressions at the forward and rearward end thereof. The splash panel 20 is provided at each side near the upper edge thereof with a toothed wheel 21 which rides on the racks 19.

The splash panel is provided with upper and lower handles 22 whereby it may be engaged and moved from and to its forward and rearward adjustments. The purpose of depressing the racks 19 at both ends is to provide a movement in a vertical direction at the extremity of the forward and rearward travel of the splash panel so that it may be raised above the upper edges of a rearward flange 23 and a forward flange 24. Therefore, when the splash panel is in rearward adjustment, its lower edge will engage behind the top edge of the flange 23 and be held in vertical position and, when moved forwardly, it seats between the forward face of the flange 24 and the rearward edge of the members 8 in closed adjustment.

The side walls of the stove body are composed of spaced plates 25 and 26 which form concealing compartments for the lower cabinet doors 27 of the stove. Each of these doors is hinged to a pair of brackets 28 at their top and bottom edges. The brackets 28 are mounted to slide on rods 29 that extend longitudinally of the compartments formed by the walls 25 and 26. In order to constitute a guide for preserving the vertical alinement of the members 27 when inserted into the compartments or withdrawn therefrom, said doors are provided with guideways 30 on their top and bottom edges, said guideways cooperating with rails 31 positioned respectively at the top and bottom of the compartments formed between the walls 25 and 26.

The front faces of the compartments for the lower cabinet walls are formed from vertical plates 32 and 33 which are spaced apart at their inner edges to form the space through which the members 27 are inserted or withdrawn. The members 27 are each preferably provided with a transverse wall 34 of a width greater than the width of the main body of said members, so that when they are inserted the walls 34 will constitute flanges that extend across the edges of the plates 32 and 33 and give a finished appearance to the stove when the stove is in open adjustment.

From the foregoing it will be understood that the construction herein disclosed provides a readily convertible stove which when in open adjustment may be used for cooking purposes and when not in use may be closed to simulate a kitchen cabinet. It therefore has a wide use in small apartments and other places where it is desired to have a convertible structure used in one adjustment for cooking purposes and in the other adjustment for an ornamental structure having utility as a table or cabinet.

I am aware that the construction may be modified in various particulars without departure from the nature and principle of the invention. I do not limit myself unessen-

tially, but what I claim and desire to secure by Letters Patent is:—

1. A stove including a stove body and a hood supported upon the rear upper end of said stove body and having a vertically extending compartment formed by each of its side walls, members adapted to be inserted in and withdrawn in vertical positions from said compartments, a support for each of said members comprising a rod extending transversely thereof near one end, a bracket supported by one wall of the respective compartments, and a rail and guideway connection between the opposite end of each of said members and the wall of said respective compartment for alining said members when inserted in and withdrawn from said respective compartments.

2. A stove including a stove body and a hood supported upon the rear upper end of said stove body and having a vertically extending compartment formed by each of its side walls, members pivoted for swinging movements and adapted to be inserted in and withdrawn from said compartments, a support for each of said members comprising a rod extending transversely thereof near one end, a bracket supported by one wall of the respective compartments, a rail and guideway connection between the opposite end of each of said members and the wall of said respective compartment for alining said members when inserted in and withdrawn from said respective compartments, and means for limiting the swinging movements of said members.

3. A stove including a stove body and a hood supported upon the rear upper end of the stove body and having a vertically extending compartment formed by each of its side walls, members pivoted for swinging movements and adapted to be inserted in and withdrawn from said compartments, a support for each of said members comprising a rod extending transversely thereof near one end, a bracket supported by one wall of the respective compartments, a rail and guideway connection between the opposite end of each of said members and the wall of said respective compartment for alining said members when inserted in and withdrawn from said respective compartments, means for limiting the swinging movements of said members, and a supporting flange supported by one wall of said respective compartments for supporting the lower edge of said members when inserted in and withdrawn from said respective compartments.

4. In a stove, a stove body, a pair of upright walls supported at the rear of the upper end of the stove body near each lateral side and each pair of walls forming a compartment opening toward the front, a plate mounted vertically in each of said compartments for forward sliding movements there-

from beyond the forward edges of the inner walls of said pairs of walls, and means for guiding said plates in said movements and permitting said plates to be moved to horizontal positions upon said stove body.

5. In a stove, a stove body, a pair of upright walls supported at the rear of the upper end of the stove body near each lateral side and each pair of walls forming a compartment opening toward the front, a plate mounted vertically in each of said compartments for forward sliding movements therefrom beyond the forward edges of the inner walls of said pairs of walls, means for guiding said plates in said movements and permitting said plates to be moved to horizontal positions upon said stove body, and a wall movable from and to vertical position between the front edges of said inner walls of said pairs of walls.

6. In a stove, a stove body, a pair of walls supported vertically above the lateral portions of said stove body at the rear thereof, a splash wall mounted vertically between said walls, and means for supporting and guiding said last named wall in movements from and to alternate vertical positions between the said first named walls.

7. In a stove, a stove body, a pair of upright walls supported at the rear of the upper end and near each lateral side of the stove body and each pair of said walls forming a compartment opening toward the front, guides mounted in said compartments, a plate mounted vertically in each of said compartments for forward sliding movements therefrom beyond the forward edges of the inner wall of said pairs of walls and being guided by said guides, and pivot devices in connection with said plates and permitting said plates to be turned from vertical positions to horizontal positions above said stove body in front of the inner walls of said pairs of walls.

8. In a stove, a stove body, a pair of upright walls supported at the rear of the upper end and near each lateral side of the stove body and each pair of said walls forming a compartment opening toward the front, guides mounted in said compartments, a plate mounted vertically in each of said compartments for forward sliding movements therefrom beyond the forward edges of the inner wall of said pairs of walls and being guided by said guides, pivot devices in connection with said plates and permitting said plates to be turned from vertical positions to horizontal positions above said stove body in front of the inner walls of said pairs of walls, and closures for said compartments movable from positions confining said plates in said compartments to positions to permit said plates to be moved from said compartments.

9. In a stove, a stove body, a plate pivoted

near each lateral edge of said body for movements to horizontal positions above said stove body to vertical positions, means for guiding said plates for sliding movements rearwardly when said plates are in vertical positions,
5 means for supporting said plates vertically in their rearward positions, a vertical wall, and means for supporting and guiding said vertical wall to and from a vertical position
10 adjacent to the rear edges of said plates when said plates are in horizontal positions above said stove body.

10. In a stove, a stove body, a pair of plates for covering the upper end of the stove body,
15 pivot devices for supporting said plates for swinging movements from positions in which said plates cover said stove body to vertical positions above the lateral sides of said stove body, means for guiding said plates for movements rearwardly from above the lateral sides
20 of said stove body, and means for enclosing said plates in the positions to which they are moved rearwardly as aforesaid.

11. In a stove, a stove body, a pair of walls supported vertically above the lateral portions of said stove body at the rear thereof, a splash wall mounted vertically between said pair of walls, means for supporting and guiding said splash wall in movements from and to alternate vertical positions between the said pair of walls, plates for covering the upper end of the stove body in front of said splash wall when said splash wall is between the forward edges of said first named walls,
30 and means for supporting said plates for movement from said positions.

EDWARD C. HOFFMANN.
